UNITED STATES PATENT OFFICE

150,907

DESIGN FOR A DRESS

John F. Strassner, New York, N. Y.

Application December 18, 1947, Serial No. 143,228

Term of patent 3½ years

(Cl. D3—26)

REFERENCES CITED

The following references are of record in the file of this patent:

Montgomery Ward Catalog No. 146, 1947, page 11, item DC 3820.

Vogue Patterns, January 1945, page 160, item 5336 A.

Vogue Patterns, Winter & Spring, 1947-48, page 174, item 6190.

To all whom it may concern:

Be it known that I, John F. Strassner, a citizen of the United States, residing in New York city, in the county of New York and State of New York, have invented a new, original, and ornamental Design for a Dress, of which the following is a specification, reference being had to the accompanying drawing, forming part thereof.

Fig. 1 is the front view of a dress showing my design, and

Fig. 2 is the rear thereof.

I claim:

The ornamental design for a dress, substantially as shown.

JOHN F. STRASSNER.
